UNITED STATES PATENT OFFICE.

HANS HANSON, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,279,861.

Specification of Letters Patent. Patented Sept. 24, 1918.

Application filed April 1, 1913. Serial No. 758,091.

To all whom it may concern:

Be it known that I, HANS HANSON, a citizen of the United States, residing in Hartford, in the county of Hartford and State of Connecticut, have invented certain new and useful Improvements in Combined Type-Writing and Computing Machines, of which the following is a specification.

This invention relates to computing machines, and is herein disclosed as applied to a combined typewriting and computing machine of the Underwood-Hanson type.

In machines of that type the numeral keys of the typewriter set up numbers on pin bars, which numbers are later carried into computing wheels by means of a general operator; said pin bars including racks which rotate said wheels to an extent determined in each case by the pins set on said pin bars. The power which drives the general operator in said machines is also used to operate a carry-over mechanism. Said carry-over mechanism is arranged to be completely operated after the numbers set up on the pin bars have been completely carried into the computing wheels.

The present invention is disclosed as applied to machines of the above-named type, and which are arranged to be used for either addition or subtraction. Machines of the types referred to are shown in the applications of B. C. Stickney, No. 696,838, filed May 13, 1912, and O. W. Olmsted, No. 691,828, filed April 19, 1912, (now Patents Nos. 1,260,728 and 1,224,314, respectively). For this purpose the racks, which drive the computing wheels, may be double racks, which may travel in uniform paths. The computing wheels preferably are mounted on an arbor forming part of a frame for said wheels. Preferably the wheels are normally out of engagement with either set of racks, but the initial movement of the general operator swings the frame carrying the computing wheels to move the wheels into engagement with one or the other of said racks, according to whether the machine is set for addition or subtraction, and turns the computing wheels accordingly.

When the computing wheels have been thus turned by the general operator, said operator preferably frees the racks from the computing wheels, and then brings into operation a carry-over mechanism. To insure

uniform operation of said carry-over mechanism on the computing wheels, said mechanism preferably forms part of the frame on which said wheels are mounted, and where a power drive is used for said mechanism, the whole frame carrying the computing wheels and carry-over mechanism is preferably pivoted on the shaft of said power drive, so that the power drive will bear the same relation to the mechanism no matter in what position the computing wheels happen to be.

In the preferred form of the present invention, the carry-over mechanism for each wheel comprises an interponent which is adapted to be set to an effective position whenever the computing wheel completes a revolution. After the general operator has completed the turning of the computing wheels, and has freed said wheels from the racks which drive them, the power shaft for the carry-over mechanism may coöperate with any such interponent as has been set by the computing wheels, to raise a pawl controlled by said interponent into mesh with the adjoining computing wheel, and then cause said pawl to turn said adjacent computing wheel one unit space. In so moving the pawl, the power device may return said pawl to its normal idle position, thus making the carry-over device ready for the next computing operation.

In its preferred form, the present invention has a single pawl for both carrying-over in adding and tens-borrowing in subtracting, and the interponent determines whether said pawl shall be operated for adding or for subtracting.

Other features and advantages will hereinafter appear.

In the accompanying drawings,

Figure 1 is a perspective view, showing the principal parts of the carry-over mechanism.

Fig. 2 is a section of a clutch on the drive shaft of said carry-over mechanism.

Fig. 3 is a sectional side view of an Underwood-Hanson combined typewriting and computing machine, showing the present invention as applied thereto.

Fig. 4 is a skeleton perspective view, showing the principal connections between the typewriter carriage, the computing wheels and the numeral keys.

Fig. 5 is a plan view, showing the general

operator and some principal parts of the computing mechanism.

Fig. 6 is a side view of a pin bar.

Fig. 7 shows the connections of the subtraction setting key.

Fig. 8 is a plan view of the same.

Fig. 9 shows a latch adapted to lock the subtraction key in its effective position.

Fig. 10 is a section through the computing wheels and some adjacent parts.

Fig. 11 is a sectional side view of the computing wheels, the frame carrying them and the carry-over mechanism all in their normal positions.

Fig. 12 is a view similar to Fig. 11, showing the parts in adding position.

Fig. 13 shows the same parts set for tens-carrying.

Fig. 14 shows the same parts while subtracting.

Fig. 15 shows the same parts set for tens-borrowing.

Figs. 16, 17, 18 and 19 are successive sectional side views of the power driven carry-over shaft and parts it carries.

Fig. 20 is a perspective view of the parts seen in Figs. 16 to 19 as assembled on said drive shaft.

Fig. 21 is a view similar to Fig. 13, but showing the mechanism in the act of carrying-over while adding.

Fig. 21^a is a view similar to Fig. 21, but showing the completion of the operation of either carrying ten or borrowing ten; this view being partly intended to illustrate the method by which overthrow of the tens-carrying and borrowing device is prevented.

Fig. 22 is a plan view of some of the connections between the typewriter keys and the pin bars.

Fig. 23 is a plan view showing the pin bars with most of the parts above them removed.

Fig. 24 shows a pin bar in its normal idle position.

Fig. 25 is a sectional front view of the parts seen in Figs. 22 and 24, showing the pins on the pin bars.

Numeral keys 1 and alphabet keys 2 operate levers 3, 4, to vibrate type bars 5 upwardly, to strike against the front side of a platen 6 mounted on a carriage 7 which travels on a rail 8, and is controlled by a rack 9 meshing with a pinion 10 connected to an escapement wheel 11.

Each type bar has a heel 12 to engage a universal bar 13 mounted on a frame 14 which operates a rocker 15 having vibratory dogs 16, 17, to engage said escapement wheel 10 and permit the carriage to feed step-by-step under the impulse of the usual spring barrel (not shown).

The computing mechanism includes an index mechanism which is operable by the numeral keys; each key having a pendent rod

18 to engage and depress the corresponding one of a series of rock arms 19 (Fig. 25), which are arrayed across the machine, being mounted upon the forward ends of rearwardly extending horizontal rock shafts 20 (Figs. 22 and 25), forming parts of linkages which depress the index pins.

Each rock shaft carries an upstanding arm 21 to engage a wrist or pin 22 upon a horizontal link 23, which extends from side to side of the machine. There are nine of these links 23, one for each numeral key, and of course, nine rock shafts and nine arms 21.

At its ends, each link connects a pair of bell cranks 24, the long arms 25 of which are connected by links 26 which descend to press down index pins 27. Each numeral key thus determines the value of the index pin which is depressed or selected, but the typewriter carriage 7 determines the denomination of the depressed pin; each link or depressor bar 26 being capable of depressing one pin in each denomination.

The index pins are arranged in rows upon bars 28 extending forwardly and rearwardly beneath the links 26, and serving eventually to rotate the number wheels in a manner presently to be described.

Normally the index pins are out of the path of movement of the depressor bars 26 (see Fig. 24), but as the paper carriage 7 feeds step-by-step, the bars 28 are displaced forwardly one after another, to positions to bring their pins within range of the depressor bars 26 (see Fig. 6), so that any bar 26 may depress the corresponding pin of the forwardly displaced pin bar. Any suitable means may be employed for displacing the pin bars forwardly one after another during the movement of the paper carriage; but there is shown herein, for the sake of illustration, a mechanism for this purpose which will presently be referred to.

Such index pins as are depressed, project below the bars 28 on which they are carried, and serve as lugs whereby said bars may be driven endwise forwardly for turning the number wheels. They are driven by means of a universal driver in the form of a transverse horizontal bar 29 which forms part of a general operator which is operated once for every calculation.

The general operator in the Underwood-Hanson combined adding and typewriting machine comprises side bars 30 (Fig. 5) which are slid in guides on the side walls of the framework and are rigidly united to form a slide or carriage; said cross bar 29 forming one of the devices for tying said bars 30 together. This carriage or general operator may be driven in any suitable way, as for instance by a crank 31 which is fixed upon a transverse horizontal rock shaft 32, journaled at its ends in the framework of

the machine, and carrying (Fig. 3) at its ends segments 33 which mesh with idle pinions 34, the latter meshing with racks 35 formed upon said general operator side bars 30.

5 A movement of the crank 31 forwardly from the Fig. 3 position causes the general operator to drive forwardly, and the bar 29 thereon engages any depressed index pins 10 27, and drives forward the bars 28 on which they are mounted.

At its forward end each of said index pin bars 28 carries an addition rack 36 normally out of mesh with a pinion 37, 15 which is fixed to a number wheel 38 forming one of a gang, there being one pin bar 28 for each number wheel. These number wheels are arranged below a sight opening 39 in the casing of the machine.

20 The cross bar 29, which engages the depressed index pins, is placed some distance behind said pins, so as to permit considerable lost motion of the general operator before the first pin can be engaged by said cross bar, and during this lost motion, the racks 36 become meshed with the number wheel pinions 37. This result is effected in the following manner: Carried upon power shaft 32 and rotated thereby is a disk 40 (Figs. 3, 4, 5, 11 and 12), which, as soon as the crank 31 starts to turn, engages a rider or pawl 41 pivoted at 42 upon an arm 43 of a lever 45, which is fixed to and turns upon a transverse horizontal rock-shaft 44, and 35 swings said lever from the normal position seen at Fig. 3 to the position seen at Fig. 12, so that a forwardly extending arm of said lever 45 may pull down, by means of a link 46, a framework which carries said number 40 wheels on an arbor 49, thus bringing the pinions 37 into mesh with said adding racks 36. Hence as the general operator continues to drive forward under the impulse of the crank 31, the pinions are turned clockwise at 45 Fig. 12, and the number wheels are turned in the same forward direction, thus performing addition; each number wheel being advanced to an extent dependent upon which of its index pins 27 was depressed.

50 After the crank 31 has been given a full forward stroke, it is swung backwardly to normal position to restore the general operator to its normal position. At the initial portion of the return stroke of the crank 31 55 and its shaft 32, the rider or pawl 41 turns counter-clockwise at Fig. 12 (the cam 40 now turning in the reverse direction from that indicated by the arrow at said figure), and by a very slight rotation of said pivot 60 42, said pawl is rendered no longer capable of supporting the arm 43. This permits springs 47 (Figs. 8, 10, and 11) to draw rearwardly V-shaped or double cam levers or arms 47^a pivoted at 47^b, which engage the 65 ends of said arbor 49 and thereby raise said

wheels clear of the rack bars 36, so that the parts 43 and 45 are restored to their normal positions.

This movement, which withdraws the pinions 37 from the addition racks 36, takes 70 place before the racks themselves start upon their return or rearward movement to normal position; such return being preferably effected by the same cross bar 29 which previously carried the racks forward. The 75 cross bar, for this purpose, engages lugs 48 pendent from the rack bars in the rear of the cross bar 29, but is arranged to have considerable idle rearward motion (enough to permit collapse of pawl 41) before en- 80 gaging said lugs 48.

At this point it may be noted that the arbor 49 on which the number wheels 38 and their pinions 37 are mounted, forms a tie-rod connecting the two sides 50 and 51 of a 85 swinging frame (Fig. 4), which has bearings or sockets at 52 to swing upon collars 53 carried by a transverse horizontal shaft 54; this shaft forming a convenient hinged support for said frame 50, 51, and keeping the 90 computing wheels always in proper relationship to the shaft 54, which is connected to the general operator and carries certain prime moving tens-carrying devices, as will presently be explained.

95 The side members 50, 51 are also connected by a tie-rod 55. The arm 45 of the shifting lever may be duplicated at 56, and the link 46 may be duplicated at 57; the shaft 44 forming a rigid connection between 45 and 56, so that the links 46, 57 pull down both sides of the number wheel shifting frame 50, 51. The arms 45, 56 may be further rigidly connected by a rod 58 to the ends of which the links 46, 57 may be pivoted.

100 Upon each of said index pin bars 28 is carried not only an addition rack 36, but also a subtraction rack 59 which is idle, as at Fig. 12, during the addition operation. This rack is parallel with the addition rack 36, but 110 above the pinion 37; and is connected by an arm 60 with the forward end of the bar 28.

To cause the machine to subtract at the driving strokes of the index bars 28, it is only necessary to move the computation pinions 37 into mesh with the subtraction racks 59, instead of the addition racks 36, so that the number wheels will be turned backwardly at the ensuing forward drive of the index bars 28.

115 When the operator desires that the machine shall perform subtraction, he presses rearwardly a subtraction key 61 on the forward end of a rod or bar 62, which extends from front to rear of the machine, and slides on a rest 62^a. Between its ends, this rod carries a cam 63 (Figs. 4, 5, 7 and 23), which during the backward thrust of the rod, engages the end of a sleeve 63^a, and forces the same endwise along the shaft 32 together 120 125 130

with the cam disk 40, which is fast to said sleeve 63^a, thus displacing the latter and silencing the pawl 41. At the same time is brought into play a second cam disk 64 also fast to said sleeve, which is effective only for the purpose of subtraction.

This disk 64 is arranged to coöperate with a follower or pawl 65, which is out of line with the pawl 41, that is, it works in a different plane; the disk 64 being shifted into the same plane as its pawl 65 when the cam disk 40 is shifted out of engagement with the pawl 41.

During the ensuing forward stroke of the general operator, the cam disk 40 will rotate idly; but the cam disk 64, as seen at Fig. 14, will engage the follower or pawl 65, and thrust down the arm 74 of the lever 45 from normal midway position to the depressed position as seen at Fig. 14, thus drawing upwardly the links 46 and 57, thereby lifting the frame 49, 50, 51, 58, and carrying the pinions 37 into mesh with the subtraction racks 59, so that the latter are enabled to turn the number wheels backwardly during the remainder of the forward stroke of the general operator. On the return stroke, the pawl 65 releases the arm 74, and then the cam arms 47^a draw the number wheels clear of the racks 59.

It will be seen that the pawls 41 and 65 are provided with springs 66 which restore the pawls to normal positions either during the endwise shifting of the cams or disks 40, 64, or at the end of the return stroke of the general operator. Normally spring 47 and arm 47^a, Fig. 11, hold the lever 45 in its midway position, and the pawls 41 and 65 stand ready for engagement with their respective cams 67 and 68, as at Fig. 3.

These cam disks 40, 64 are splined to the shaft 32 by means of a pin 69 carried on an arm 70 fixed to said shaft, and passing through a hole in disk 40.

The tens-carrying or carry-over devices comprise an idle pinion 71 meshing with a rack 72 on the general operator, to connect said operator with a pinion 73 on the horizontal transverse shaft 54 having a helical series of cams or tappets 75 for carrying tens at the addition operation. This shaft 54 turns in only one direction, and is operated only during the return stroke of the general operator; being for this purpose connected by a ball clutch mechanism 76 to the pinion 73, as seen at Fig. 2. A spring 132 holds a detent 132^a (see Fig. 5) to prevent backward rotation of the shaft 54.

Each number wheel (except that of lowest denomination) has an individual train of mechanism for connecting it to this power-driven tens-carrying shaft 54, but the train is normally broken, and hence the tappets or cams 75 are all normally ineffective. Each number wheel 38 (except that of highest

denomination) has a starting tooth 77, the function of which is to establish a connection from the number wheel of next higher denomination to the tens-carrying shaft 54.

Each of the trains of connecting devices 70 includes (Fig. 1) a pawl 78 to mesh with a gear 79 fixed upon the number wheel; the pawl preferably having multiple teeth 80, or being in the form of a short rack, as shown. Each pawl is normally out of mesh with its gear wheel 79, but the starting tooth 77 operates means for positioning the pawl so that the pawl will, at the proper time, come up into mesh with its pinion, and at the same time provide for the subsequent driving movement of the pawl.

To this end, the pawl 78 has a pin-and-slot connection at 81 with a two-armed lever or tumbler which is in the nature of an interponent device between the power driven tens-carrying cams 75 and the number wheel rotating pawl 78; this lever being pivoted between its ends upon an arbor 82, and having a short arm 83 provided with a pin 84 in the path of said starting or setting tooth 77.

The number wheel 38 turns in the direction of the arrow, or clockwise, as at Fig. 12, to perform addition. The setting tooth 77, at the completion of a full revolution of said number wheel 38, engages and depresses the pin 84 together with the arm 83, swinging said interponent lever or rocker to the position seen at Fig. 13.

The lower arm 85 of said lever or rocker 100 has a slot to engage with the pin 81 on the tens-carrying pawl 78, which by the movement of the rocker to the Fig. 13 position is drawn back from the normal position at Fig. 12. Upon said arm 85 is a cam-like tooth 86, which at Fig. 13 is seen as having been swung into the path of the associated tappet 75 on the tens-carrying shaft 54, the function of the latter being to act upon said tooth 86, and thereby return the rocker 110 forward to its normal position. During such return movement, the rocker arm 85 carries with it the pawl 78, which, however, has in the meantime been swung up into mesh with the gear 79 of the number wheel next higher 115 than that which carries the setting tooth 77, whose movement has just been mentioned.

The forward swing of the pawl 78 is effected by the engagement of the tappet 75 with the rocker tooth 86; there being provided upon the tens-carrying shaft 54 a cam 87 which depresses the rear end of the pawl 78, and lifts the forward end thereof into mesh with said gear 79 as at Fig. 21; the pawl being supported between its ends 125 by a rod 88 which rigidly connects arms 89 pendent from the side plates 50, 51, thus forming part of said frame comprising the arbor 49 and extending forwardly from the collars 53 on said shaft 54, to rock up and 130

down for shifting the adding pinions into and out of mesh with the driving racks 36.

By means of said pawl 78, the higher number wheel is advanced one point by the time 5 the rocker reaches the Fig. 12 position. The cam 87 has a continuation or dwell portion 90 which holds down the rear end of the pawl 78 during the wheel driving movement, and which thereupon releases said pawl and 10 permits the forward end thereof to be snapped down by a spring 91 out of mesh with the gear 79; a spring detent 92 engaging the latter to hold the number wheel in position.

15 At the subtracting operation, which includes what may be called tens-borrowing, the setting tooth 77 on the number wheel, which is traveling counter-clockwise (Fig. 14), lifts the arm 83 and swings the rocker 20 to the Fig. 15 position.

The upper arm 93 of the rocker has a tooth 94 which is swung into the path of a cam or tappet 95 on the power shaft 54; the tappets 95 being spirally arranged and being 25 paired with the tappets 75. The tappets 95 are in different planes from the tappets 75, and the tooth 94 is correspondingly offset from the arm 93. The cam 87 depresses the 30 front arm 96 of the pawl 78 and elevates the rear arm 96 of the pawl 78 and elevates the front arm thereof into mesh with the gear 79, and then the tappet 95 camming or acting upon the tooth 94, swings the rocker 93, 85 to the normal midway position at Fig. 12; thus drawing backwardly the pawl 78. At 35 the conclusion of the tens-borrowing operation, the cam 87 releases the rear arm 96 of the pawl, and the forward arm of the latter is drawn down by the spring 91 as before.

40 Each cam 90, together with its associated tappet 75 and 95, forms a group, and said groups, as seen at Fig. 20, are arranged spirally on the shaft 54, so that the computing wheels are successively operated by the 45 carry-over devices from lower to higher denominations.

It will be seen that the rocker 85, 93 may be regarded as a tumbler or interponent, since it disposes the pawl 78 to be operated 50 by the tappets 75, 95 on the power shaft 54; and that the operation of said rocker, as effected by the tappets, resembles the operation of a pallet in an escapement mechanism.

55 The rocker or tumbler 85, 93 is held in any of its three positions (Figs. 3, 4, 11 to 15) by means of a detent arm 97 pivoted upon a rod 98, which rod connects the side arms 50, 51 just in front of the rod 55, and said 60 detent arm is pressed downwardly by a spring 99 coiled around the rod 55; the detent arm having three notches 100, 101 and 102 to engage a pin 103 on the tumbler to hold the same in any of the three positions 65 seen at Figs. 12 to 15.

It will be seen that the sides of the notches 100 and 102 are extended to form hooks which positively stop the rocker 85 at each of its extreme positions; although, if desired, this rocker 85 may be positively arrested by the engagement of either 86 or 94 with the circular hub portions 103^a of the disks on which the cams or tappets 75 and 95 are formed, Figs. 16 and 20.

It will be understood that, owing to the 75 speed with which the power-driven tens-carrying shaft 54 revolves, the tappet 75 is apt to operate the tens-carrying lever 85, 93 at such speed, in swinging it to the normal position seen at Fig. 21^a, that the 80 lever, with the pawl 28 and the number wheel, might overthrow; and to guard against this, there are provided on the shaft 54 stops 95^a, concentric with said shaft and merging into or being continuations of the 85 tappets 95. These stops 95^a are so placed that each occupies the path of the tooth 94 on the associated rocker 85, 93, when the latter is swung by the tappet 75 from the Fig. 21 position to the normal position at Fig. 90 1, 3, 11, 12 and 21^a. Of course the shaft 54 is revolving, and it is only for a brief period that the stop or dwell portion 95^a remains in the path of the tooth, shoulder or projection 94; but this is sufficient to prevent overthrow of the rocker 85, 93.

Overthrow is prevented at the operation of borrowing tens, in a similar manner. At Fig. 15 the member 85, 93 is shown as rocked over to begin a subtraction operation; and after the pawl 78 is elevated, the tappet 95 engages the tooth or shoulder 94 and swings it to the position at Fig. 21^a, at which time the shoulder or projection 86 will be arrested by stop 95^b which is a continuation 105 of the tappet 75. This positively prevents overthrow of the rocker 85, 93 at the subtraction or tens-borrowing operation, the stop or dwell 95^b being sufficiently long for this purpose.

The number wheels have individual tens-carrying trains each comprising the tumbler, the detent arm, the pawl, and the gear 79. It will be understood that all of these tens-carrying trains are mounted upon the swinging frame 50, 51, and, therefore, that the number wheels with their pinions, detents 92, gears, and tens-carrying trains swing up and down as a unit about said power shaft 54, which serves as a support for the rear 115 end of said frame, as already explained. Owing to the fact that these members swing up and down as a unit, the setting tooth 77 is enabled to perform its functions properly whether the wheels are in the addition position as at Fig. 13, or in the subtraction position as at Fig. 15.

The reason for arranging the tappets 75 (and tappets 95) in spiral relation around the power shaft 54, is that this enables tens 120 125 130

to be carried upon the number wheels *seriatim*, so that the machine is capable of carrying "1" over from wheel to wheel throughout the entire set at the tens-carrying operation; the operation of one tens-carrying train being finished before the operation of the next higher train can begin.

The pawls 96 may be guided at their rear ends in a comb 104, and any suitable provision may be made for guiding their forward ends, as for instance said forward ends may be confined between the racks 36 and the tumbler arms 85.

The subtraction key rod 62 is held back during the subtraction operation by means of a latch 105 (Figs. 3, 4 and 7), which is pivoted at 106 upon the framework and is held by a spring 107 in a notch 107^b in the rod or bar 62. This latch is automatically released at the conclusion of the return stroke of the general operator, after the operation of the tens-borrowing or carry-over mechanism has been completed. This latch-releasing operation occurs simultaneously with the raising of the universal plate 108, which restores the index pins 27 to normal positions. The plate 108 is operated in the usual manner, and is pivoted as usual upon bell cranks 109 connected by a link 110. During the last part of the return stroke of the general operator, a pawl or abutment 111 on a side bar 30 usually engages an arm 112 connected to one of the bell cranks to cause the latter to swing, and the plate 108 to rise, thereby lifting the index pins 27. Thereupon the arm 112 trips off from the abutment 111 and the plate 108 drops.

During the rise of the plate 108, an arm 113 connected to one of said bell cranks swings down and strikes a heel 114 on the latch 105, thus withdrawing the same from the notch 107^a in the subtraction key rod or bar 62, so that a spring 115 may snap the latter forwardly to normal position, as seen at Fig. 3.

This returns the sleeve 63^a and the cam 64 to their normal positions in which the machine adds.

It will be seen that the arm 113 is fixed upon a rock shaft 116 upon which one of the bell cranks 109 is fixed. If it be desired to retain the key 61 in its rearward position, a bolt 117 (Figs. 8 and 9) may be slid to the left by means of a finger-piece 118 to engage a notch 119 in the rod 62; a spring detent 120 holding the bolt in either position.

The index pin bars 28 may be guided at their forward ends in a comb 121 (Fig. 3), and may be confined between said comb and a rod 122 forming part of the fixed framework of the machine. At their rear ends the bars may be guided in a fixed comb 123.

The means for setting said index pin bars 28 forwardly, so as to bring the index pins

27 into register with the pin-depressing linkages 26, may be of any suitable construction, and for the sake of illustration there is shown a device for this purpose comprising vertical levers 124 pivoted between their ends at 125, the lower ends of these levers being adapted to strike the rear ends of the index pin bars 28. At their upper ends, these levers are engageable by beveled dogs 126 pivoted upon lugs 127 on the carriage 7; the levers being arranged at letter-space intervals, so that at each letter-feeding movement of the carriage 7, one of the levers 124 is vibrated, and the index pin bar 28 of corresponding denomination is set forwardly, so as to bring its pins within range of the depressors 26.

The levers 124 are so formed that the denominational order of their upper ends is the inverse of their lower ends (see Fig. 4). The dogs 126 are individually pivoted so as to permit them to ride idly over the ends of the levers 124 while the carriage is being returned. Returning springs 128 are provided for the levers 124, and pivoted fingers 129 are pressed by springs 130 against shoulders 131 on the index pin bars 28, to return them one after another from the positions to which they are displaced by the levers 124; said fingers 129 riding idly on the top edges of said index pin bars 28 during the wheel driving movements of the latter. Other devices may be employed for connecting the index pin bars 28 to the carriage 7.

Reference is made to United States Hanson Patent No. 905,421 of December 1, 1908 for further explanation of the operation of machines of this general class.

Variations may be resorted to within the scope of the invention, and portions of the improvements may be used without others.

Having thus described my invention, I claim:

1. In a computing machine, the combination with computing wheels and numeral keys, of rack bars, means set by said keys for determining how far said rack bars shall rotate said computing wheels, an arbor on which said computing wheels are journaled, carry-over devices for said wheels, a frame comprising said arbor and carrying said carry-over devices, and a power-driven shaft for operating said carry-over devices, on which shaft said frame is pivoted.

2. In a computing machine, the combination with computing wheels and rack bars each comprising an addition rack and a subtraction rack for turning said computing wheels to a predetermined extent, of a general operator for driving said rack bars, a shaft driven by said general operator, a frame for said computing wheels normally holding them clear of said rack bars, a lever for moving said frame, and cams on said

shaft for selectively moving said computing wheels in said frame into and out of mesh with the racks on said rack bars.

3. In a computing machine, the combination with double racks for temporarily registering numbers, of computing wheels normally out of mesh with said racks into which the numbers so registered are carried simultaneously, said racks effective in one direction only, and for adding engaging said wheels on one side, a key settable to cause said racks to engage said wheels on the opposite side to cause numbers to be subtracted from said wheels, carry-over means operable after said wheels are turned and in a direction dependent on the turning of said wheels, and means for automatically separating said wheels and racks and for releasing said subtraction key when said numbers are so carried into said wheels and the carry-over is completed.

4. In a computing machine, the combination with computing wheels, of carry-over devices for operating said wheels after said wheels have been all set, a power-driven shaft rotated in one direction only, and pawls driven by said power shaft to cause said carry-over devices to be effective for adding or subtracting according to whether the computing wheels are adding or subtracting.

5. In a computing machine, the combination with rack bars, of computing wheels, an arbor carrying said computing wheels, a rack on each rack bar on each side of said computing wheels, a shaft lying between said racks on which said arbor is pivotally supported, carry-over devices for said computing wheels carried on said pivotal support, and a shaft forming part of said pivotal support for driving said carry-over devices to an extent determined by said computing wheels.

6. In a computing machine, the combination with rack bars each comprising two racks, of an arbor lying between said racks, computing wheels journaled on said arbor, a frame of which said arbor forms a part for shifting said computing wheels, carry-over devices in said frame, interponents set by said computing wheels to operate said carry-over devices according to which rack the computing wheels engage, and pawls for turning said computing wheels in opposite directions as determined by the setting of said interponents.

7. In a computing machine, the combination with computing wheels and a carry-over tooth on each wheel, of an interponent for each computing wheel set by its carry-over tooth, a floating pawl for the adjacent computing wheel set by its interponent to rotate said wheel in either direction, a power-driven shaft, means carried by said power-driven shaft for moving said pawl into engagement

with its wheel, and separate means on said shaft for then rotating it.

8. In a computing machine, the combination with computing wheels and a carry-over tooth on each of said wheels, of an interponent pivoted adjacent each wheel, an arm on said interponent arranged to be struck by said carry-over tooth, a pawl set by said interponent, a power-driven shaft comprising means for moving said pawl into mesh with its wheel, and separate means for then driving the pawl in a manner determined by said interponent.

9. In a computing machine, the combination with computing wheels, of a carry-over tooth on each wheel, an interponent pivoted adjacent to each wheel, an extension on said interponent on each side of said pivot, a pawl set by said interponent and moved thereby, and a power-driven shaft arranged to drive said pawl by one of said extensions according to the manner said interponent has been set by its carry-over tooth.

10. In a computing machine, the combination with computing wheels, of a carry-over pawl for each wheel, means for moving said pawl in either direction, and means for moving said pawl into engagement with its computing wheel to actuate the same, and then actuating the computing wheel by returning the pawl to normal position.

11. In a computing machine, the combination with computing wheels, of a carry-over pawl for each wheel, a power-driven shaft normally ineffective with reference to said pawls, means on said power-driven shaft for successively raising each pawl into engagement with its computing wheel, and means on said shaft for moving said pawls in either direction to rotate said wheels.

12. In a computing machine, the combination with computing wheels, of an interponent for each wheel, a carry-over tooth on each wheel for setting its interponent, a detent for holding the interponent in said position, a pawl positioned by said interponent, and a power-driven device for driving said interponents to turn said wheels and restore said interponents to normal position.

13. In a computing machine, the combination with computing wheels, of a rack bar for rotating each wheel but normally ineffective with reference to said wheel, a carry-over rack bar movable into engagement with said wheel, an interponent to which the carry-over rack bar is pivoted to selectively carry it away from normal position, a general operator for said first-named rack bars, and a power-driven device for said carry-over rack bars adapted to move them to normal position to drive the wheels and arrest the rack bars against overthrow to arrest the computing wheels.

14. In a computing machine, the combination with computing wheels, of a power-

driven shaft rotating in one direction only, carry-over interponents set by said computing wheels, means on said interponents for causing said power-driven shaft to move 5 them in either direction, and a carry-over pawl for each interponent by which each interponent drives its wheel.

15. In a computing machine, the combination with computing wheels, of an interponent pivoted adjacent each wheel, means 10 on each wheel for rotating each interponent in either direction, a carry-over pawl moved by said interponent to advance the wheel, and a power-driven device arranged to re- 15 store said interponents to normal position, and in so doing to turn said computing wheels by said pawls.

16. In a computing machine, the combination with computing wheels, of a carry-over 20 interponent pivoted adjacent each computing wheel, means for setting each interponent in either one of two positions away from normal, a power-driven shaft, and means for returning the set interponents to 25 normal to turn said computing wheels as determined by the set interponents.

17. In a computing machine, the combination with computing wheels, of carry-over pawls, a power-driven device, an interponent 30 moving each of said carry-over pawls, and means on said interponent for causing said power-driven device to move it in either direction to move its pawl.

18. In a computing machine, the combination 35 with computing wheels, of a pivoted interponent adjacent each wheel, a carry-over pawl moved by said interponent, an extension on said interponent upon each side of its pivot, and a power-driven device to move 40 said interponent by said extensions.

19. In a computing machine, the combination with computing wheels and rack bars for turning them, of a general operator for 45 said rack bars, means for moving said general operator, a frame in which said computing wheels are carried, a connection for moving said frame to cause said wheels to mesh with their rack bars by said moving means, carry-over pawls also carried in said frame, 50 and separate means for causing said carry-over pawls to engage with their computing wheels.

20. In a computing machine, the combination with computing wheels and separate 55 rack bars for driving them in either direction, of cams revolving with the movement of said rack bars, a frame in which said wheels are carried, a lever comprising tappets arranged to selectively coöperate with 60 said cams to move said frame to cause said wheels to mesh with their selected rack bars, and means for shifting said cams to cause said frame to be moved in the desired direction to so select the rack bars.

65. 21. In a computing machine, the combina-

tion with computing wheels, of separate rack bars for turning them in either direction, a frame in which said computing wheels are carried, an arm comprising tappets for moving said frame to move said wheels into 70 mesh with either of their rack bars, a general operator for moving said rack bars, cams turning with the movement of said general operator, and a key for selectively setting said cams to move said frame. 75

22. In a computing machine, the combination with computing wheels, of rack bars each comprising two racks, a frame in which said wheels are carried, a lever for moving said frame to cause said wheels to mesh with 80 either rack, a general operator for driving said rack bars, cams turning with the movement of said general operator, and a key for setting said cams to cause them to selectively move said wheels into engagement with 85 either rack.

23. In a computing machine, the combination with carry-over devices, of a power-driven shaft, spirally-arranged cams on said power-driven shaft to make said carry-over 90 devices effective, and spirally-arranged tappets on said shaft to operate the effective carry-over members.

24. A tens-carrying mechanism comprising a rocker movable from normal position 95 by the computing wheel, a shaft having a tappet to return said rocker, a pawl operated by said rocker for advancing the next higher computing wheel, and a stop on said shaft to prevent overthrow of said rocker upon 100 reaching normal position.

25. A carry-over mechanism comprising a rocker movable from normal position in either direction by the computing wheel, a shaft having tappets to drive said rocker 105 from either of its abnormal positions back to normal position, a pawl operated by said rocker for either advancing or retracting the next higher computing wheel, and stops on said shaft to prevent overthrow of said 110 rocker in either direction upon returning to normal position.

26. A carry-over mechanism comprising a rocker movable from normal position in either direction by the computing wheel, a shaft having tappets to drive said rocker 115 from either of its abnormal positions back to normal position, a pawl operated by said rocker for either advancing or retracting the next higher computing wheel, and stops on 120 said shaft to prevent overthrow of said rocker in either direction upon returning to normal position; said rocker having two projections or shoulders, one for addition and one for subtraction, to be engaged by 125 said tappets and stops, and the addition tappet being continued to form the subtraction stop, and the subtraction tappet being continued to form the addition stop.

27. In a combined typewriting and com-

- puting machine, the combination with computing wheels adapted to add or subtract, of carry-over devices for moving said wheels in opposite directions, and a shaft independent 5 of said wheels and always turning in the same direction, having spirally arranged members adapted to drive said carry-over devices in either direction.
28. In a combined typewriting and computing machine, the combination with computing wheels and a carry-over shaft, of a frame carrying said wheels mounted on said shaft, and carry-over devices driven by said shaft adapted to carry or borrow on said 10 wheels.
29. In a computing machine, the combination with computing wheels, of a carry-over tooth on each wheel, an interponent set by said carry-over tooth, and a toothed member engaging the adjacent computing wheel to positively rotate it one unit space in either direction as determined by said interponent, and to positively arrest it when so turned.
30. In a computing machine, the combination with computing wheels, of a carry-over tooth on each wheel, an interponent set by 15 said carry-over tooth, a toothed member engaging the adjacent computing wheel to rotate it in either direction one unit space as determined by said interponent, and to positively arrest it, and a power driven shaft for so driving said toothed member.
31. In a computing machine, the combination with computing wheels and a carry-over tooth on each of said wheels, of an interponent pivoted adjacent each wheel, a bar on said interponent arranged to be struck by said carry-over tooth, a toothed member set by said interponent, and a power driven 20 shaft for moving said toothed member into mesh with its wheel, and then turning it in a manner determined by said interponent, and then positively arresting it.
32. In a computing machine, the combination with computing wheels, of a carry-over tooth on each wheel, an interponent pivoted adjacent each wheel, an extension of said interponent on each side of its pivot, a toothed member set by said interponent and moved 25 thereby, and a power driven shaft arranged to drive said toothed member by one of said extensions according to the manner said interponent has been set by its carry-over tooth, and to positively arrest the computing 30 wheel by the other extension.
33. In a computing machine, the combination with computing wheels and a carry-over tooth for each wheel, of a toothed member for each wheel, means for setting said 35 toothed member to turn said wheel in either direction, a power driven member arranged to successively operate all said toothed members, and means connected to said power driven member for positively arresting each 40 wheel, when so turned.
34. In a computing machine, the combination with computing wheels and a carry-over rack-bar for each wheel, of means for moving said rack-bar in either direction, a carry-over tooth for said rack-bar, a power driven shaft for successively operating all 45 said rack-bars, and means for arresting said rack-bars by said power driven member to positively hold the computing wheels against over-throw.
35. In a computing machine, the combination with computing wheels, of a carry-over rack-bar for each wheel, means for moving said rack-bar in either direction, means for moving said rack-bar into engagement with 50 its computing wheel to actuate the same by returning the rack-bar to its normal position, and means for positively preventing over-throw of the carry-over wheel by its rack-bar.
36. In a computing machine, the combination with computing wheels, of a carry-over rack-bar for each wheel, a power driven shaft normally ineffective with reference to 55 said rack-bars, means on said shaft for successively raising each rack-bar into engagement with its computing wheel, and means on said shaft for moving said rack-bars in either direction to rotate said wheels, and then to positively arrest them.
37. In a computing machine, the combination with computing wheels, of an interponent for each wheel, a carry-over tooth on each wheel for setting its interponent, a detent for holding the interponent in said position, a rack-bar positioned by said interponent, a power driven device for driving said interponents to turn said wheels and return said 60 interponents to normal position, and means for positively preventing over-throw of said computing wheels by said interponents.
38. In a computing machine, the combination with computing wheels, of a power driven shaft rotating in one direction only, carry-over interponents set by said computing 65 wheels, means on said interponents for causing said power driven shaft to move them in either direction, a carry-over rack for each interponent, and means effective on its interponent for positively preventing 70 overthrow of any computing wheel.
39. In a computing machine, the combination with computing wheels, of a carry-over interponent pivoted adjacent each computing wheel, means for detaining each interponent in any one of three positions, a power driven shaft, means for turning said computing wheels as determined by the detained interponents, and means for positively preventing over-throw of the computing wheels 75 by their interponents.
40. In a computing machine, the combination with carry-over devices, of a power driven shaft, spirally arranged cams on said shaft to make said devices effective, spirally 80

arranged tappets on said shaft to operate the effective carry-over devices, and spirally arranged members on said shaft to positively prevent over-throw by said carry-over devices.

41. In a decimal computing machine, the combination with a series of decimal dial wheels, of a series of racks arranged to drive said dial wheels in opposite directions, a series of carry-over racks normally occupying an intermediate position, means for giving said carry-over racks a predetermined offset at the passing of the associated dial wheels to zero when completing a revolution, the offset being in one direction or the other according to whether addition or subtraction is being carried on, and means for enabling said carry-over racks to transmit the offset to the next higher dial wheels to effect carry-overs, by returning the associated carry-over racks to their intermediate position.

42. The combination with a series of computing wheels, of a series of rack bars for driving said computing wheels, and normally disengaged therefrom, means for effecting a relative shifting movement between said rack bars and said computing wheels to effect a driving engagement before a driving movement of said rack bars, a traveling carriage, a tappet carried by said carriage, and a series of levers directly engaged by said tappet, and directly engaging said rack bars to advance them slightly in

the direction of their driving movement while disengaged from said computing wheels to effect denominational selections.

43. The combination with a series of computing wheels, of a gear on each of said computing wheels, rack bars normally disengaged from said gears, an indexing mechanism for determining the extent of movements of said rack bars, spring means for maintaining said rack bars normally in such a position that said indexing mechanism will be ineffective, a traveling carriage, and a series of levers operated directly from said carriage, and directly engaging said rack bars to render effective said indexing mechanism *seriatim* for each of said rack bars when said rack bars are disengaged from said gears by advancing said rack bars slightly in the direction of drive against the tension of said spring means.

44. The combination with a series of dial wheels, of a series of rack bars for driving said dial wheels, a traveling carriage, a tappet carried by said carriage, and a series of levers mounted on a fixed pivot arranged to be cammed rearwardly by said tappet, to force forwardly by direct engagement said rack bars to effect denominational selections.
